ATTORNEY

UNITED STATES PATENT OFFICE.

HENRY ILL, OF NEWARK, NEW JERSEY.

DESIGN FOR A CASTER-PIN.

SPECIFICATION forming part of Design No. 25,521, dated May 19, 1896.

Application filed December 18, 1895. Serial No. 572,601. Term of patent 14 years.

To all whom it may concern:

Be it known that I, HENRY ILL, a citizen of the United States, residing at Newark, in the county of Essex and State of New Jersey, have 5 invented a certain new and useful Design for Caster-Pins; and I do hereby declare the following to be a full, clear, and exact description of the invention, such as will enable others skilled in the art to which it pertains to 10 make and use it, reference being had to the accompanying drawings, which form part of this specification.

My invention relates to a novel design for 15 caster-pins; and it consists in the novel configuration shown.

The design is clearly illustrated in the accompanying drawings, in which—

Figure 1 is a side elevation of my novel design of caster-pin, and Fig. 2 is a cross-section of the same, taken on line x in Fig. 1.

The leading feature of my novel design is a 20 caster-pin having a plain cylindrical portion a' , which terminates in an oval head a^2 , surrounded by a beaded or beveled edge a^3 , as shown. The upper portion a of the caster-pin is of a slightly-increased diameter over 25 the diameter of the plain cylindrical portion a' , said enlarged portion being ornamented with an especial configuration, having a rope-like appearance. Said enlarged portion a is 30 bounded at the point where it joins the plain cylindrical surface a' with angularly-arranged portions a^4 , which produce a zigzag edge, and from which extend a number of longitudinal

ridges a^5 and depressions a^6 , which are helical 35 curves and form half-turns to produce the said rope-like ornamentation of the cylindrical surface a , and also produce a many-pointed star-shaped figure in cross-section, as illustrated in Fig. 2. Said helical ridges and 40 depressions are closely disposed on said enlarged surface a of the caster-pin and terminate directly at the upper and free edge of said pin, as represented in Fig. 1.

The essential and novel feature of the design for a caster-pin is a plain cylindrical portion a' at the lower part of the pin and the upper and slightly-enlarged portion a , having many longitudinal and helical ridges and depressions, forming a rope-like ornamentation 50 of the said upper part of the caster-pin, producing a many-pointed star when the caster-pin is viewed from the top, and said enlarged portion having the rope-like ornamentation bounded by a zigzag edge at the point where 55 it joins the plain cylindrical surface of the pin.

Having thus described my invention, what I claim is—

The design for a caster-pin, substantially 60 as herein shown and described.

In testimony that I claim the invention set forth above I have hereunto set my hand this 17th day of December, 1895.

HENRY ILL.
